UNITED STATES PATENT OFFICE.

HUGH M. MARSH, OF CHICAGO, ILLINOIS, ASSIGNOR TO CATHERINE A. FOX, OF CHICAGO, ILLINOIS.

CURTAIN-ROLLER SUPPORT.

Application filed December 12, 1921. Serial No. 521,595.

To all whom it may concern:

Be it known that I, HUGH M. MARSH, a citizen of the United States, residing at Chicago, Cook County, State of Illinois, have invented certain new and useful Improvements relating to Curtain-Roller Supports, of which the following is a specification.

The present improvements are in respect to mountings for sustaining a curtain roller in its operative position adjacent to a window opening. One of its objects is to provide supporting means whereby the roller may be easily removed and replaced without losing the spring pressure developed in the body of the roller for rotating it. Its chief object is to provide roller-supporting means adapted for use where it is desired to maintain in substantially a given plane the curtain which is paid off of the roller, as where it is desired to close the window opening substantially tightly by the curtain whatever amount of curtain is paid off of the roller.

An important application of these improvements will be found in connection with ventilating closures for window openings of the general character set forth in the patents to Catherine A. Fox No. 1,268,228 of June 4, 1918 and No. 1,249,369 of December 11, 1917.

A ventilating closure of that general character is also illustrated in the accompanying drawings, which form a part of this specification, and in which Figure 1 is a fragmentary face view of window parts having the present improvements applied thereto; Fig. 2 is a sectional view, on a somewhat enlarged scale, as on the line 2—2 of Fig. 1; Fig. 3 is a still more enlarged view, as on the line 3—3 of Fig. 1, showing in full lines the operative position of the roller and its connections, and in dotted lines the position of parts when it is desired to release the roller, as for removing the curtain therefrom as for cleaning it; Fig. 4 is a view at right angles to the view of Fig. 3 in the direction of the arrow 4—4; Fig. 5 is a view showing the mounting at the other end of the roller, as on the line 5—5 of Fig. 1; and Fig. 6 is an end view of the roller with a curtain thereon showing the locking pawls and the attachment of the curtain to the roller.

The window sash comprises the usual stiles 10 and the horizontal rail 11, and is

mounted for up and down movement in the frame comprising the jambs 12 and the sill 13. The mountings or supports for the roller ends include respectively plates 15 and 16 secured as by screws directly upon the sash rail 11. The housing or cover 17, of light sheet metal, is secured as by bolts 18 to the roller supports. The roller and its supports are within this housing, and move with the sash when it is raised and lowered.

A plurality of spring clips 20 hold the lower edge of the curtain 21 readily releasably upon the sill 13, and when the sash is raised the curtain 21 pays off of the roller 22 and covers the window opening, thus providing for ventilation while at the same time excluding insects, dirt and dust. The curtain or screen 21 will ordinarily be of fabric having appreciable space between the warp and woof threads for the admission of air. A material known as scrim is suitable for the purpose.

In order that the curtain may effectively close the window opening for the exclusion of objectionable matter the mountings are so formed that as the curtain pays off of the roller and the diameter of the roller and curtain thereon is decreased, the roller and the curtain thereon will move bodily toward the desired plane when the curtain is being paid off, and in the reverse direction when the curtain is being wound thereon.

The plane in which it is desired to maintain the curtain is defined by upright rest members 25 which may be of thin sheet metal, and are shown as angle iron sections secured to the jambs 12 in front of the sash stiles 11 and resting substantially against these stiles, the flat-surfaced guides 25 extending at least as high as the roller travels in its upward movement.

From Figs. 2, 3 and 5 it will be observed that the curtain or screen 21 on the roller rests against these upright guides or movement-limiting bars 25, and it is clear that so long as the curtain or screen on the roller is maintained against these members 25 the curtain will lie against the members 25 in any operative position in which the sash may be, the lower end of the curtain being held by the clips 20 so that the curtain rests against these guides 25.

Turning to Fig. 5 we see the right-hand end of the curtain roller viewed from in front, as in Fig. 1. This end of the cur-

tain is provided with the usual axial cylindrical pindle 30. The mounting at that end includes a vertical plate 31 having an upwardly-extending recess 32 and a downwardly and inwardly slanting recess 33, the latter forming a pocket constituting a bearing for the pindle 30. A spring 34 draws upon a lever 35 pivoted at 36, which lever has an arm overlying the slots 32 and 33. 10 When it is desired to remove or insert the roller the pindle 30 moves the lever 35 out of the way, as shown by dotted lines, permitting the pindle to follow the grooves 33 and 32. The lower end of the recess 33 is 15 so formed that the pindle 30 may move toward and away from the upright guide 25, while following the downwardly-inclined path provided for it by the groove 33, this downwardly-inclined path insuring that 20 the pull or tension upon the curtain caused by the coiled spring, which is to be understood as being within the roller for producing such tension on the curtain, will maintain the rolled curtain against the guide 25 25 at that end of the roller.

Turning to Figs. 2, 3 and 4, the mounting at the left-hand end of the roller, as it would be viewed in Fig. 1, comprises a vertical plate 40 to which is pivoted at 41 a swinging arm 42 which is substantially L-shaped and to which is pivoted at 43 a second swinging member 44 which has a slot adapted to receive and hold the usual rectangular projection 45 issuing from that 30 end of the roller and to which projection is secured the coiled spring S (Fig. 1) within the body of the roller and which it is desired to put under tension for rotating the roller relative to the projection 45. The 40 vertical supporting plate 40 has a relatively large middle recess 46 opening toward the guide 25 and when the roller is mounted on the swinging arm 44 the curtain on the roller will be maintained against the guides 25 by the coiled-spring pressure upon the curtain. As the curtain pays off of the roller that end of the roller will descend in an arc corresponding with the simultaneous 45 lowering of the pindle 30 (Fig. 5) in the groove 33.

The roller 22 carries the usual pivoted dogs 47 adapted to engage with notches in a disc connected with the projection 45 to hold the projection 45 in some temporarily-fixed relative position. Curtain rollers of the kind herein referred to are so well known that it is only necessary to point out here the character of the roller employed. As will be observed from Fig. 6 55 the notches 50 are opposite the ends of the projection 45 as there viewed. When the projection 45 is in its more horizontal position, as shown in Fig. 3, there is no tendency of a dog 47 to enter a notch 50, since the dog is gravity-controlled. The cur-

tain may therefore always be paid off of the roller without interference by the dogs, and, also, so long as the projection 45 is in its substantially horizontal and operative position, as in Fig. 3, the dog 47 will not 70 catch in a recess 50 when the curtain is wound upon the roller.

In order to lock the projection 45 by a dog 47 means are provided for changing the direction of the projection 45 as viewed 75 in Fig. 3. From Figs. 3 and 4 it will be noted that a link 54 is also pivoted at one end upon the pivot 43, and at its other end the link 54 has a laterally-projecting pin 55 passing through a hole in the end 56 of a 80 lever arm 57 (Fig. 4) pivoted at 58 upon the supporting plate 59, there being a bell crank extension 60 of this lever having a finger piece 61. From Fig. 3 it will be noted that the pin 55 is below the pivot 43 and this link 54 therefore holds the pivoted end of the swinging arm 44 against movement when the device is in operation. If, however, the finger piece 61 is moved in the direction of the arrow (4-4, Fig. 3) the 85 connection at 55 (Fig. 3) will be raised, as shown by the dotted line positions of the link 54 and the pivot 43 will be carried so far away from the guide 25 that the roller 90 and the curtain thereon may swing downward in front of the guide and the rectangular projection 45 will then assume the substantially vertical position shown by dotted lines in Fig. 3, one of the notches 50 being then in position to receive the 95 end of one of the pawls or dogs 47, thus locking the projection 45 and maintaining the spring pressure.

With the roller parts so locked it is only 105 necessary to move the pindle 30, Fig. 5, out of the slots 33 and 32 and then withdraw the roller, the projection 45 easily coming out of its retaining slot in the swinging arm 44. When it is desired to 110 replace the roller the finger piece 61 is again moved so as to bring the swinging part 44 into its lowermost position, the rectangular projection 45 is inserted in the 115 slot in the part 44, and the pindle 30 is inserted and moved through the grooves 32 and 33, Fig. 5, and thereupon the curtain is moved bodily upward and the finger piece 61 is released. Thereupon by inserting the lower or free end of the curtain 120 (having the usual wood strip 65) beneath the clips 20 the device as a whole is ready for use.

The result of this construction is that as 125 the sash is raised and lowered the curtain is maintained in close association with the curtain-overlapping guides 25, whether only a few turns or many turns of the curtain are paid off of the roller or automatically rewound upon it, and the roller with the curtain upon it may be readily removed without 130

sacrificing the spring-pressure desired for re-winding the curtain.

Means for conveniently securing the curtain upon the roller are shown in Fig. 6 as comprising a longitudinal recess in the roller at 60, the recess having a constricted opening at 61, this recess extending from one end of the roller to the other, and the end edge of the curtain being enlarged as by 10 cording it, that is turning the material over a cord and sewing it, this enlarged edge being inserted in the recess at 60 and being held against retraction when in use by the reduced space between roller parts at 61. 15 The curtain may thus simply be drawn into this recess from one end of the roller where it is held in a manner which does not interfere with the substantially circular winding of the various plies of the curtain. 20 I contemplate as being within the scope of these improvements various departures from what is specifically herein illustrated and described, as indicated in the appended claims.

25 I claim:

1. The combination of means defining a window opening, a curtain roller extending thereacross, a curtain wound on said roller, a mounting at each end of the roller and secured adjacent to the window opening, interengaging means between the roller at each end and the mounting thereat for holding the roller rotatably, each of said mountings being formed to provide a path of movement of the end of the roller thereat toward a predetermined plane in which the curtain is to lie when paid off of the roller, and means for limiting the movement of the roller toward such predetermined plane 30 whereby the place where the curtain pays off of the roller is in such predetermined plane at all stages of the paying off of the curtain from the roller.

2. The combination of means defining a window opening, a curtain roller extending thereacross, a curtain wound on said roller, a mounting at each end of the roller and secured adjacent to the window opening, interengaging means between the roller at each 45 end and the mounting thereat for holding the roller rotatably, each of said mountings being formed to provide a path of movement of the end of the roller thereat toward a pre-

determined plane in which the curtain is to lie when paid off of the roller, and stop 55 means against which the curtain on the roller presses when being paid off of the roller for limiting the movement of the roller toward such predetermined plane whereby the place where the curtain pays off of the roller 60 is in such predetermined plane at all times when the curtain is being paid off of the roller.

3. The combination of means defining a window opening, a curtain roller extending 65 thereacross, a curtain wound on said roller, a mounting at each end of the roller and secured adjacent to the window opening, interengaging means between the roller at each end and the mounting thereat for holding 70 the roller for automatic movement in a path toward a predetermined plane when the curtain is drawn upon so as to unwind some thereof from the roller, and means for limiting the movement of the roller toward such 75 predetermined plane whereby the place where the curtain unwinds from the roller is in such predetermined plane at all times when being so unwound therefrom.

4. The combination with a rotatable curtain roller, of a curtain wound thereon, means for holding the ends of the roller for automatic movement toward a vertical plane substantially parallel with the axis of the roller when the roller is horizontally disposed and when a down-hanging portion of the curtain is pulled upon to unwind the curtain from the roller, and means for limiting the movement of the roller so as to maintain that part of the curtain which is being 80 unwound from the roller substantially in 85 said plane during the unwinding operation.

5. A mounting for a curtain roller comprising a swinging arm pivotally mounted, said arm having means spaced from the pivotal mounting for engaging a projection at the end of the roller to hold the roller, means for holding the pivotal connection substantially in a given relative position, and means for releasing said pivotal-connection-holding 95 means whereby said swinging arm may move in a direction away from said given position for providing further movement of the swinging arm.

HUGH M. MARSH.
